DISPENSING TRAY FOR PLASTIC BAGS OR THE LIKE

Kenneth A. Smith, 6520 SE. 77th Ave.,
Portland, Oreg. 97206

Filed Nov. 20, 1972, Ser. No. 308,229

Term of patent 14 years
The portion of the term of the patent subsequent to
Apr. 11, 1986, has been disclaimed

Int. Cl. D9—99
U.S. Cl. D52—2 C

FIG. 1

FIG. 2

FIG. 4

FIG. 1 is a plan view of a dispensing tray for plastic bags or the like, showing my new design.

FIG. 2 is a front elevational view;

FIG. 3 is a rear elevational view; and

FIG. 4 is a side elevational view thereof looking from the left of FIG. 2.

I claim:

The ornamental design for a dispensing tray for plastic bags or the like, as shown.
